UNITED STATES PATENT OFFICE.

EDWARD M. WRIGHT, OF MADISON HEIGHTS, VIRGINIA.

PLOW-POINT PATTERN-PLATE.

1,365,214.

Specification of Letters Patent. Patented Jan. 11, 1921.

Application filed December 24, 1919. Serial No. 347,146.

To all whom it may concern:

Be it known that I, EDWARD M. WRIGHT, a citizen of the United States, residing at Madison Heights, in the county of Amherst and State of Virginia, have invented a new and useful Plow-Point Pattern-Plate, of which the following is a specification.

This invention has reference to plow point pattern plates, and its object is to eliminate certain objectionable features which are present in prior pattern plates.

Plow points of the character to which this invention relates are each provided with an overhanging lug to lock the point securely to the standard. To produce the lug cavity in the mold, it has been the custom to use a detachable movable piece operated by a cam or similar device. Such movable piece complicates the structure, wherefore, in accordance with the invention, that part of the pattern producing the cavity, to in turn form the locking lug, is made a hinged structure which is readily yieldable to the removal of the cope piece of the flask when lifted from the pattern plate, the yielding being entirely automatic and the construction being of extreme simplicity. Moreover, provision is made for the disposition of any loose sand which may be dislodged by the turning of the lug pattern on its hinge.

In producing molds from plow point plates in molding machines, it has been the practice to heat the plates so that the damp sand will not adhere thereto. In accordance with one method, a kerosene torch is placed under the plate to produce the necessary heat, but this is injurious and detrimental to health because the operator is liable to inhale the smoke and gases from the torch. Alcohol lamps and charcoal are sometimes used, but these methods are likewise injurious to the health of the operator and produce an irregular and very unsatisfactory heat. These methods produce more or less soot, which is liable to clog up necessary mechanisms that are sometimes put on the plates.

The invention contemplates the employment of an electrically energized heating unit at the rear face of each pattern element or plate, which heating unit is clean, uniform, does not give off any fumes or gases, and may be controlled to a nicety.

The invention will be best understood from a consideration of the following detailed description taken in connection with the accompanying drawings forming part of this specification, with the understanding, however, that the invention is not confined to any strict conformity with the showing in the drawings, but may be changed and modified so long as such changes and modifications mark no material departure from the salient features of the invention as expressed in the appended claims.

In the drawings,

Figure 1 is a perspective view of one of the pattern plates.

Fig. 2 is a perspective view of the other pattern plate.

Fig. 3 is a bottom plan view of the plate shown in Fig. 1.

Fig. 4 is a section on the line 4—4 of Fig. 3.

Fig. 5 is a section on the line 5—5 of Fig. 2.

Fig. 6 is a perspective view of the hinged member constituting the pattern block for the point locking lug.

Referring to the drawings, there are shown two pattern plates A and B, respectively. The plate A is provided with a pattern 1 and the plate B with a pattern 2, one plate being used to make the cope impression and the other plate to make the drag impression, and the two impressions produce the mold.

The plate A comprises a frame 3 surrounding a mass 4 of concrete or other such refractory material, in which is lodged in a recess thereof the pattern 1 exposed on one face of the plate, and the plate B is similarly constructed, being provided with a frame 5 and a mass 6 of concrete embedding the pattern 2. In the process of producing the mold, the two plates are used in conjunction with the cope and drag in the usual manner. The general construction of the two plates is that customarily employed and needs no special description.

In plow points of the character indicated in the drawings, the point is provided with a linear locking lug by means of which it is held to the plow standard. As heretofore produced, an overhanging locking lug is formed by means of a pattern member comprising a detachable movable piece operated

by a cam or similar device slidable underneath the plate. This arrangement is productive of a cavity in the mold.

In accordance with the invention, a different and much simpler means for the production of the locking lug is employed. The pattern 2 is provided with an enlargement 7 which, in the finished plow point, produces the basic portion of a locking lug. The enlargement 7, which is in the form of an elongated and gradually thickened rib, terminates in spaced ears 8 having a tongue 9 lodged between them and secured to them by a transverse hinge or pivot pin 10. The tongue 9 is located on one end of a block or piece 11 constituting a continuation of and being normally in line with the enlargement 7 and forms the overhanging portion of the locking lug in the finished plow point. The block 11 is free to turn about the axis of the pivot 10 so that when the cope piece of the flask is lifted from the plate B, the block yields in a direction to readily draw from the sand without material disturbance thereof and without the necessity of providing manipulating means for moving the pattern device, for forming the overhanging lug, out of interfering relation with the sand. The hinged block constitutes a simple and very efficient automatic means for permitting the block to give and clear from the sand, but it is to be understood that other suitable automatic means may be employed for the purpose, for the invention in this respect is not necessarily confined to a hinged block.

The hinged block 11 has a nose end 12 beveled on its underside and overhanging the corresponding portion of the pattern 2, and under the basic portion of the hinged block, a passage 13 is formed through the pattern 2 to the basic portion of the plate B, so that any sand which may be loosened by the raising of the hinged block will find escape through the passage 13 and not pack.

Carried by the respective plates A and B, underneath and spaced from the pattern 1 or 2, as the case may be, is an electric heating element 14 comprising a grid 15 of resistance wire or other suitable material confined between insulating sheets 16 or baked in refractory insulating material, and provided with a conducting cord 17 leading away from the heating element to be connected to a suitable source of electric current. The heating element 14 is made to conform approximately to the pattern 1 or 2, and after the sand is applied, the current is turned on and the heat produced passes through the pattern to the sand. The purpose of the heating element is to prevent

damp sand from adhering to the plate and pattern, and this can be brought about with a nicety by the electric heater because the heat may be applied directly where wanted, has no fouling effects, and may be regulated within close limits. 65

The bottom of each plate is in the form of a pan-like plate 18 riveted or otherwise secured to the frame 3, wherefore to receive and hold the mass 4 of concrete in the plate A or B, as the case may be. As Fig. 4 shows, screws 19 extending through the heating element hold the latter directly against the pan 18 and pass through the intervening concrete and into the pattern plate 1 or 2, as the case may be. 70 75

So far as I am aware, I believe that I am the first to provide an electric heating arrangement for pattern plates. Experience 80 has shown it to be vastly superior to the usual heating methods. Moreover, the electric heater permits the application of the heat, readily regulated, in the most efficient position to dry the damp sand. 85

What is claimed is:

1. A plowpoint pattern plate provided with a projection on the mold-forming face and gradually rising therefrom, a block hinged at one end to the projection and constituting a substantially linear continuation thereof in overhanging relation to the corresponding portion of the pattern, and a passage leading from the block for the escape of any sand which may be loosened by 90 the raising of the block. 95

2. A plow point pattern plate provided with a projection on the mold-forming face, and a freely yieldable block constituting a continuation thereof in overhanging relation to the corresponding portion of the pattern, said pattern having a passage therethrough leading from beneath the yieldable block to carry loose sand therethrough. 100

3. A plow point pattern plate provided 105 with a portion for forming an overhanging locking lug on the finished plow point, said pattern member having the overhanging portion automatically yieldable to the withdrawal of the cope member from the pattern 110 plate, and said pattern plate having a passage therethrough leading from beneath the yieldable portion of the locking-lug pattern member.

In testimony, that I claim the foregoing 115 as my own, I have hereto affixed my signature in the presence of two witnesses.

EDWARD M. WRIGHT.
